UNITED STATES PATENT OFFICE.

CHAUNCEY E. TURNER, OF SEATTLE, WASHINGTON.

WRENCH.

Application filed June 15, 1925. Serial No. 37,063.

My invention relates to an improvement in wrenches having relatively movable jaws.

An object of the invention is to overcome the back-lash or loose movement usually prevalent in the action of this type of wrench.

Another object of the invention is to accomplish the foregoing practically without the addition of parts or altering the appearance of the wrench as heretofore made.

The invention possesses other objects and features of advantage, some of which, with the foregoing, will be set forth in the following description of the preferred form of my invention which is illustrated in the drawings accompanying and forming part of the specification. It is to be understood that I do not limit myself to the showing made by the said drawings and description, as I may adopt variations of the preferred form within the scope of my invention as set forth in the claims.

Referring to said drawings:

Figure 1 is a side elevation of a wrench made in accordance with my invention.

Figure 2 is a fragmentary sectional view of the head portion of the wrench.

Figures 3 and 4 are side views of the worm pieces.

The wrench to which the invention in its present form is particularly adapted usually comprises a stock 5 provided at one end with a fixed jaw 6 and a guideway 7 in which a movable jaw 8 is slidably held. The latter is generally provided with a toothed rack 9 engaged by a suitable worm adapted for manual manipulation and usually mounted for rotation on a screw-shaft 12 preferably removably held in the stock.

Heretofore the worm has been made in one piece, and in order to provide the necessary freedom in operation, a slight clearance between the worm and rack teeth had to be provided for. Such clearance, however, produces a proportionate back-lash and looseness of the wrench parts during the operation thereof, and since the looseness becomes enhanced with the continued use of the wrench, the accuracy of adjustment of the latter soon becomes considerably impaired.

In accordance, however, with my invention the worm is formed of two pieces 13 and 14 each of which is mounted for rotation on said shaft 12, and adapted to individually engage the teeth of the rack 9;

The pieces are arranged to be held against relative rotative movement but are permitted relative axial displacement toward and from each other. As here shown connection between the pieces to provide the foregoing relation, is effected by removing complementary segments from adjacent portions of the pieces and allowing the longitudinally cut faces 16 and 17 of the unmoved segments 18 and 19 to abut.

Encircling the shaft 12 and interposed between the piece 16 and the side 21 of the stock opening 22 in which the worm is loosely fitted, is a spring 23 which urges the piece 16 axially toward the piece 17. Owing, however, to the fact that the latter is permitted axial displacement from the former while both are engaged with the rack, pressure of the spring will force the piece 16 against the teeth of the rack, rather than against the piece 17, and the latter will receive the force of the spring only through the medium of the rack. In this manner in any given position of the jaw 8, the piece 17 will bear against the side 24 of the opening 22 and prevent movement thereof in one direction, while the piece 16 will with a resilient force oppose the movement of said jaw in a reverse direction. Thus while the worm and rack are provided with the necessary clearance, the frictional engagement of the several parts will positively eliminate the undesirable back-lash, and the accurate adjustment and proper action of the wrench will be assured.

I claim:

1. A wrench comprising a stock having a fixed jaw, a movable jaw slidably mounted on said stock and provided with a toothed rack, and a pair of rotatable worms in said stock having the threads thereof arranged to maintain threaded engagement with said teeth in said rack and adapted for axial displacement relative to each other.

2. A wrench comprising a stock having a fixed jaw, a movable jaw slidably mounted on said stock and provided with a toothed rack, and a pair of rotatable worm-threaded members on said fixed jaw capable of axial but not rotative displacement relative to each other and adapted to simultaneously maintain threaded engagement with the rack of said movable jaw.

3. A wrench comprising a stock having a fixed jaw, a movable jaw slidably held on said stock and provided with a rack, a pair

- 2
- of axially aligned rotatable members mounted in said stock and maintaining threaded engagement with said rack independently of each other, said members being capable of 5 axial displacement with respect to each other, and means for resiliently pressing one of said members axially against said rack.
4. A wrench comprising a stock having a fixed jaw, a movable jaw slidably held on said stock and provided with a toothed rack, a rotatable worm mounted in said stock adapted to engage said rack to slide the jaw, and means independent of said worm operative directly against a tooth of said rack to 10 resiliently press said rack longitudinally to force other teeth thereof against said worm.
5. A wrench comprising a stock having a fixed jaw, a slidable jaw mounted on said stock and provided with a toothed rack, a 15 pair of rotatable axially aligned worms mounted in said stock and arranged to have their threads engage between the teeth of said rack in all rotative positions of the worms, said worms being held against relative rotative movement but capable of relative axial displacement while in engagement 20 with said rack, and a spring pressing one of said worms axially against the said teeth.
6. In a wrench, a stock having a fixed 25 jaw, a slidable jaw mounted in said stock and provided with a toothed rack, means for sliding said latter jaw comprising a two piece worm member mounted for rotation in said stock each of said pieces having the 30 thread thereof arranged to maintain a threaded engagement with the teeth of said rack and capable of axial movement toward

each other while so engaged, said pieces being held against relative rotative movement, and a spring interposed between one of said pieces and adjacent portion of said stock whereby said piece will be urged axially 40 against said rack teeth and the latter will in turn impart a resilient force on the other piece.

7. In a wrench, a stock having a fixed jaw, a slidable jaw mounted on said stock and provided with a toothed rack, a screw-shaft in said stock, a two piece worm member held together on said shaft for rotation as a whole, each of said pieces having the thread thereof arranged to maintain a threaded engagement with the teeth of said rack and capable of axial movement toward each other while so engaged, and a spring 45 encircling said shaft and interposed between one of said pieces and adjacent portion of said stock arranged to press said piece axially against the teeth of said rack whereby the latter may exert a corresponding pressure against the other piece.

8. A wrench comprising a stock having a fixed jaw, a movable jaw slidably mounted on said stock and provided with a toothed rack, and rotatable worms in said stock having the threads thereof arranged for resilient engagement with the teeth of said rack, the threads of one worm engaging sides of 50 rack teeth oppositely related to those engaged by the other worm.

In testimony whereof, I have hereunto set my hand at Seattle, Washington, this 5th day of June, 1925.

CHAUNCEY E. TURNER.
